J. H. JOHNSON.
APPARATUS FOR MOISTENING SHOES.
APPLICATION FILED MAY 23, 1913.

1,117,852.

Patented Nov. 17, 1914.

UNITED STATES PATENT OFFICE.

JOHN H. JOHNSON, OF MANCHESTER, NEW HAMPSHIRE, ASSIGNOR, BY MESNE ASSIGNMENTS, TO UNITED SHOE MACHINERY COMPANY, OF PATERSON, NEW JERSEY, A CORPORATION OF NEW JERSEY.

APPARATUS FOR MOISTENING SHOES.

1,117,852

Specification of Letters Patent. Patented Nov. 17, 1914.

Application filed May 23, 1913. Serial No. 769,434.

To all whom it may concern:

Be it known that I, JOHN H. JOHNSON, a citizen of the United States, residing at Manchester, in the county of Hillsboro and State of New Hampshire, have invented certain Improvements in Apparatus for Moistening Shoes, of which the following description, in connection with the accompanying drawings, is a specification, like reference characters on the drawings indicating like parts in the several figures.

In connection with the pulling-over and lasting operations on boots and shoes it has been found very advantageous to moisten, by means of steam or vapor, the parts of the shoe that are pulled or stretched most severely during these operations. These parts are, of course, the toe and vamp portions of the upper, although it has also been proposed to treat the heel portions of the upper in a similar manner. While various forms of apparatus for steaming the toes of shoes have gone into general use, these devices are all, so far as I have been able to learn, open to the objection that it is almost impossible to use them without wetting the insoles and the lasts, and that great care must be exercised in order to avoid burning and discoloring the upper stock. The lasts, of course, are very likely to split or "check" if the moisture penetrates into the wood; and most insoles will either shrink when moistened with steam or hot vapor or will become very brittle on drying out after being moistened in this manner. Uppers made from certain grades of stock also require considerable care in handling since, if subjected to vapor at too high a temperature they will shrivel up and burn, or if hot water is spattered on them it will burn the stock and will spot colored leathers.

It is an important object of this invention to devise a moistening apparatus of the character above indicated that will avoid these objections. To this end I have designed a novel form of apparatus and have devised a peculiar construction of nozzle which, in the preferred form, is adapted to project between the last and the upper of the shoe and to direct steam or vapor against the part of the upper material which it is desired to moisten, while protecting the last and other portions of the shoe from contact with the steam or vapor.

Referring now to the accompanying draw-

ings, Figure 1 shows in front elevation an apparatus constructed in accordance with the present invention and designed particularly for moistening the toes of shoes preparatory to lasting them; and Fig. 2 is a sectional view of the apparatus taken on the plane indicated by the line 2—2. Fig. 1, the shoe rest being shown in side elevation.

The apparatus shown comprises a casing 2 supporting on its upper side two nozzles. 65 Each of these nozzles consists of a body 4, having a base that is tapped to receive a nipple 6 by which it is connected to the casing, and a hollow semi-cylindrical portion inclined forwardly at a considerable angle 70 and constituting the back wall of the nozzle. This wall is curved forwardly at its upper end and is rounded to fit under the toe portion of a partly lasted shoe. The nozzle also has a front wall 8 that is removably secured 75 to the body 4 by means of two screws 10, and this wall is concaved or recessed to receive the toe portion of a last, as will be clearly understood by reference to Fig. 2. The two walls of the nozzle are spaced apart to afford a free passage for steam or vapor between them and they unite at their upper ends to form a thin overhanging lip that is adapted to fit snugly between the toe of the last and the toe portion of the upper of a 85 shoe. This lip is apertured on its upper side, as indicated at 12, to direct the steam or vapor passing through the nozzle against the under surface of the upper, the lower wall of the lip being imperforate so that it 90 will protect the last from contact with the vapor or any water of condensation.

In the apparatus shown in the drawings only two nozzles are provided, since this number is sufficient for an apparatus designed to be used in connection with the lasting machine; but obviously any desired number of nozzles may be employed, and they may be modified in shape to meet particular conditions.

In order to support the shoes for the moistening operation a shoe rest is provided consisting in the form shown of three metal straps 14, each secured to the side of the casing 2 by means of screws 16, and a fourth 105 strap 18 that is riveted to the upper ends of the straps 14 and is bent between the adjacent members 14 to form depressed portions in which the shoe may conveniently rest, as shown in Fig. 2. The supports 14

are inclined away from the casing 2 at an angle such that the toes of the shoes will be properly presented to the nozzles of the apparatus.

5 In order to supply steam to the casing a pipe 20 is extended longitudinally through the casing and is secured by the usual nuts and washers necessary to make steam-tight joints, one end of the pipe being capped, as shown at 22. This pipe is perforated on its lower side as indicated at 24 to admit steam into the casing 2 and a drip pipe 26, threaded through the bottom of the casing, carries away any water that may condense within 10 the casing. Steam may be supplied to the casing 2 from any convenient source, but if delivered directly from a supply system it should be conducted to the casing at a very low pressure in order to avoid burning the 15 upper material. In this connection, however, it should be noted that, with the present arrangement, the steam does not come in direct contact with the upper leather but must first pass through the lining and toe 20 stiffener so that much of the danger of burning the upper leather that is experienced with other devices is avoided. It is preferable to have the steam supplied at such a low pressure that, when it issues from the delivery openings 12, it will not be steam, as that term is used in a technical sense, but will be merely a warm moist vapor. If steam must be used at comparatively high pressures for this work it usually will be preferable to 25 have the drip pipe 26 project into the body of the casing 2 to a height above the level of the apertures 24 in the steam inlet pipe 20 so that the steam, as it is discharged from the inlet pipe, will be delivered into water. 30 The vapor rising from the body of water in the casing will travel through the nozzles to the shoe.

It is obvious that, in the arrangement shown, the casing 2 acts chiefly as a support 45 for the nozzles and the shoe rest and as a conduit for the steam or vapor that is to be used in treating the shoes. Consequently, this member may be replaced by any equivalent device, as for instance by a steam pipe 50 forming a continuation of the connections by which steam is conducted to the apparatus.

In using the apparatus in connection with the lasting machine, the sides and heel of a shoe are first lasted and the shoe is then 55 placed on the rest 18, the toe portion of the last being positioned under the lip of the nozzle while the toe portion of the upper of the shoe rests on the nozzle. The steam or vapor emitted through the apertures 12 penetrates the upper material and moistens and softens it so that it can be easily worked over 60 the bottom of the last and disposed smoothly about the toe of the last. Usually the workman has two shoes in the apparatus practically all the time. The apertures in the noz-

zles are so located that they direct the vapor on to those portions only of the upper that it is desired to soften. The vapor finds its way out along the toe of the shoe under the lining and other part of the upper and does not come in contact with either the last, insole or other part of the shoe that could be damaged by it. A further advantage of this arrangement is that very little steam escapes into the room.

Any water of condensation that gathers in the nozzles drains into the casing 2 and is carried away by the drip pipe 26. If the apertures 12 become clogged they may be cleaned out readily by removing the screws 80 10 and taking off the front wall 8 of the nozzle. It has also been found advantageous to use an apparatus similar to that above described, or one having the same essential characteristics, to moisten the toe portions of 85 shoes just before they are pulled over. This is particularly true where the independent system of lasting is followed as distinguished from the team system, since in the independent system the shoes are usually 90 assembled several days before they reach the pulling-over machine and, in the meantime, even the cement or gum used in the stiffeners has become thoroughly dry. A moistening apparatus designed to be used with a 95 pulling-over machine should, however, be able to accommodate more shoes than an apparatus designed for use with a lasting machine, one capable of handling four shoes at once being well adapted for the former machine.

It will be readily understood that, while I have disclosed the best form of the invention of which I am at present aware, this disclosure is made by way of illustration rather than limitation; and that the apparatus is susceptible of many changes while still employing the same principles and while still using the essential elements of the invention, and such changes I regard as coming within 110 the scope of this invention.

Having thus described my invention, what I claim as new and desire to secure by Letters Patent of the United States is:

1. In an apparatus for moistening the toe 115 of a shoe while the last is in the shoe, a nozzle shaped to extend between the toe of the last and the upper of the shoe on the last and to direct vapor against the under side of the toe portion of the upper.

2. In an apparatus for moistening the toe of a shoe while the last is in it, a nozzle shaped to extend over the toe of the last and under the upper of the shoe, said nozzle being apertured in the wall next to the upper to direct vapor against the under side of the upper.

3. In an apparatus for moistening the toe 125 of a shoe while the last is in the shoe, a nozzle having an imperforate front wall 130

- concaved to fit over the toe of the last and having a back wall lying substantially parallel to but spaced apart from the front wall to afford a space between said walls for the 5 passage of vapor, said walls terminating in a thin overhanging lip curved to fit between the toe of the last and the upper of the shoe on said last, and said lip being apertured to direct vapor against the upper of the 10 shoe.
4. In an apparatus for moistening the toes of shoes, a nozzle comprising a body of substantially semi-cylindrical shape having its upper end curved forward to fit under the 15 toe portion of a partly lasted shoe, and a front wall for said nozzle concaved to fit over the toe portion of a last, said walls terminating in a thin overhanging lip and the upper wall of said lip being apertured to 20 direct vapor against the under surface of the toe portion of the upper of the shoe.
5. In an apparatus for treating shoes before the lasting operation has been completed and while the lasts are in the shoes, 25 the combination of a support constructed to sustain one or more shoes for treatment, and means for conducting vapor between the last and the upper of a shoe sustained by said support, said means being constructed to direct the vapor against the under side of the 30 shoe upper and to prevent it being directed against the last.
6. In an apparatus for moistening the toe of a shoe while the last is in the shoe and before the lasting of the shoe has been completed, a nozzle having a lip portion shaped to extend between the toe of the last and the upper of the shoe, in combination with 35 a support arranged to sustain the shoe with the toe of the last under said lip and the toe portions of the upper on said lip, said lip being apertured to direct vapor against the upper.
7. In an apparatus for moistening the toes of shoes before they are lasted and while the lasts are in the shoes, the combination of a casing adapted to contain vapor, a support constructed to sustain a plurality of shoes with their toes extending toward said casing, and means for conducting vapor 45 from said casing and directing it against the under sides of the uppers of the shoes sustained by said support.
8. In an apparatus for treating shoes before the lasting operation has been completed and while the lasts are in the shoes, a vapor conducting means constructed and arranged to extend between the last and the shoe upper and to direct the vapor away from the last and against the under side of the 55 upper.
9. In an apparatus for moistening a portion of a shoe while the last is in the shoe and before the lasting operation has been completed, a nozzle shaped to project between the last and the upper and constructed to direct vapor against the under side of the upper while protecting the last from contact with the vapor.

In testimony whereof I have signed my name to this specification in the presence of two subscribing witnesses.

JOHN H. JOHNSON.
